UNITED STATES PATENT OFFICE.

LUTHER W. ALLINGHAM, OF LOS ANGELES, CALIFORNIA.

HELIOMOTOR.

SPECIFICATION forming part of Letters Patent No. 514,669, dated February 13, 1894.

Application filed June 8, 1893. Serial No. 476,965. (No model.)

To all whom it may concern:

Be it known that I, LUTHER W. ALLINGHAM, a citizen of the United States, residing at Los Angeles, Los Angeles county, State of California, have invented an Improvement in Heliomotors; and I hereby declare the following to be a full, clear, and exact description of the same.

My invention relates to the class of apparatus by which the rays of the sun may be concentrated and steadily directed to one spot during the whole of the period of sunshine.

The object of my invention is to focus the sun's rays and thus produce heat enough for many practical purposes, such for example, as heating water, fruit drying, steam generation, &c.

My invention consists essentially of a car moving in an arc of a circle round a fixed point, suitable sections of reflectors carried by the car, and adjustable to focus the reflected rays upon the focal point, and means for automatically adjusting the car and the reflectors so that the reflections may be on the focal surface during the whole period of sunshine.

My invention also consists in the novel construction and combination of the parts of the apparatus hereinafter fully described and specifically pointed out in the claims.

Referring to the accompanying drawings for a more complete explanation of my invention,—Figure 1 is a perspective view of my heliomotor. Fig. 2 is a perspective view showing the connections at the back of one reflector. Fig. 3 is a view showing the form of an adjustable connection between links and levers. Fig. 4 is a radial cross section through the base of the heliomotor. Fig. 5 is a view of one section of reflectors.

The car consists of a suitable frame-work A, the parts of which are united together and suitably braced and supported.

The car rotates around and is partly supported on a pivotal point a placed at or near the center of gravity.

Under the car and placed so as to bear its weight is a circular plate a' which moves over stationary wheels w in the manner of an ordinary turn-table.

Upon the cars are suitable frames for supporting the reflectors and adjusting appli-

ances, and frame a² for supporting any suitable surface or thing to be focused upon.

The car is rotated round this pivotal point a by the appliances to be now described. The purpose of this rotation is to present the reflecting surface to the sun during the whole day. The power is taken from a shaft or other means (not shown) by which a regular stroke can be obtained. From this the stroke is communicated by a rigid link o to a lever O which works a pawl in a ratchet wheel H. This ratchet wheel is on the same shaft h as an arm or crank h' which communicates a stroke by means of a link o' to a lever O' which works a ratchet wheel H'. This ratchet wheel is on the same shaft as a fusiform windlass G which winds a chain F. This chain passes round the circular plate a' beneath the car and is fastened to it at such a point as will give the chain power over the car to produce motion round the pivotal point a. The purpose of the fusiform windlass is to produce the gradually increasing rate of motion necessary to keep pace with the rate of sun's apparent motion from the horizon to the meridian and to decrease the rate of motion corresponding to its rate from the meridian to the horizon again. The various connections between the rigid links o and o', and the levers O and O' are adjustable to regulate the rate of motion given to the fusiform windlass.

The sections of reflectors are made of a number of small reflectors b' arranged in the section in such a manner that the aggregate surface of small reflectors forms a broken concave surface. The degree of concavity of the sections varies with the distance at which they are placed from the focal point. Thus the farther away from the focal point, the less the concavity. The concavity varies inversely to the distance from the focal point. Back of the sections, and at or near the center, each section of the outer tiers is hinged to the bracket c on the section bar b. This hinge permits motion round a line parallel to the horizontal axis, but prevents motion round its vertical axis, except as later described. The central sections, represented by B', swing upon pivotal points b² at each extremity which permit motion only about the horizontal axis. At or near the center of the back of each section of reflector, a tilting lever p

is attached, the uses of which will be presently described. These levers are united by rigid links l to the adjacent levers above, thus uniting the levers of all the sections in one tier. All these connections are adjustable. One of these levers, in each tier of sections, is lengthened out as at P' , and a weight W is attached, suitable to exactly counter-balance the united forward tilting tendency of the whole tier of sections.

The section bar b will now be described: It consists of the bar inclined at a suitable angle from the perpendicular, and bearing brackets c to which the sections B of reflectors are pivoted. The bar is axially pivoted at each end to its supports, so as to permit it and the corresponding tier of sections to be directed inward toward the center. This motion is controlled by the levers d as will be shown.

20 The section bar is used only for the outer rows of sections.

The means for adjusting the sections to focus their reflections on the focal point will now be described. There are two necessary motions for the accomplishment of this purpose. These are, first, a motion round a line parallel to the horizontal axis of each section; and, second, a motion round a line parallel to the vertical axis of each of the outer sections, which is accomplished by turning the section bar b on its end pivots, and thus directing the surface of its reflectors toward the center. Both these motions are originated by the motion of the car around its pivotal point a acting on the eccentric double guide rail g . The center of the circle of which this double eccentric guide rail is an arc is in a line running north and south through the pivotal point a . It is at a suitable distance from the pivotal point so that the guide rail may be suitably eccentric to the pivotal point. Thus the nearest point in the guide rail to the pivotal point, will be that point at which the line running north and south cuts the guide rail. Each successive point on each side increases in distance from the pivotal point. This guide rail is firmly fixed to the foundation below so as to be immovable by moderate force. Between the parts of this rail, a wheel M moves which lies beneath the central portion of the car, and is carried by a sliding bar m' to which the upright m is firmly attached. This bar slides out and in, parallel with the central portion of the car by which it is carried. Thus as the central portion of the car travels toward the point at which the line drawn through the pivotal point a and the center of the eccentric rails intersects the

55 said rails, the upright m approaches the pivotal point. Thus a motion is produced toward the pivotal point from morning till noon, and away from it from noon until night, by the receding of the upright m . This motion 60 of the upright is communicated to the crank arm s by means of a rigid link s' . The crank arm s acts upon the rock-shaft S which bears

other crank arms s^2 . From each crank arm s^2 rigid links as L are attached to the links l which connect the tilting levers p of the sections. By this combination, the motion from the upright m is communicated to the tilting levers p of the sections, and by them the sections receive motion round lines parallel to their horizontal axes. Thus from morning 75 until noon the sections are tilted backward to accommodate the rise of the sun, and forward from noon until night. All these attachments of links and levers, &c., are adjustable to regulate the motion as desired. 80 The second motion, namely, directing the reflectors to the center, is produced as follows: As the upright m is moved toward the center, motion is given to the double lever K by means of the rigid link k acting on the lever Q at right angles to the double lever K . Each arm of the double lever K is connected by rigid links k' to the levers d of the section bars b of the opposite sides. Thus from morning 85 until noon, the upright m moves toward the center a and this produces motion about the center of the double lever K , each arm thrusting the attached links outward. The levers d to which these links are attached are similarly acted upon, and the section bars b 90 are thus turned on their pivotal ends and the reflections directed inward. This motion is reversed from noon until night. All attachments of the various links and levers are adjustable to increase or decrease motion. 95

The various adjustable attachments can be conveniently made by a device which may be thus described.

Referring to Fig. 3, a piece like a clevis R fits loosely over a lever and is fastened to it 105 by means of a bolt or set screw r . On one or both sides of this, the bolt or set screw passes through the extremities of a spring clip r' which fastens on a rigid link. Thus the clevis can be moved along the lever and properly 110 adjusted. The rigid link passes through the spring clip r' and can be fastened at any suitable place.

Having thus described my invention, what I claim as new, and desire to secure by Letters 115 Patent, is—

1. In a heliomotor, the combination of a car adapted to turn about a fixed pivotal point, a series of adjustable reflectors carried by the car, a fixed eccentric guide rail, and mechanism engaging said rail and operated by the movement of the car to adjust the reflectors to focus their rays upon a given point or focal surface, substantially as herein described.

2. In a heliomotor, the combination of a car 125 having a fixed pivotal point about which it turns, a swinging reflector carried by the car and means for adjusting the reflector to focus its rays constantly upon one point, consisting of a fixed eccentric guide rail, and connections therefrom to the reflector, substantially as herein described.

3. In a heliomotor, the combination of a car adapted to turn about a fixed pivotal point, a

series of adjustable reflectors carried thereby and mounted so as to turn about a line parallel to their horizontal axes, a fixed eccentric guide rail and mechanism engaging said rail and operated by the movement of the car to turn said reflectors about said line, substantially as herein described.

4. In a heliomotor, the combination of a car adapted to turn about a fixed pivotal point, a series of adjustable reflectors carried thereby and mounted so as to turn about a line parallel to their vertical axes, a fixed eccentric guide rail, and mechanism engaging said rail and operated by the movement of the car to turn said reflectors about said line, substantially as herein described.

5. In a heliomotor, the combination of a car adapted to turn about a fixed pivotal point, a series of adjustable reflectors carried thereby and mounted so as to turn about lines parallel to both their horizontal and their vertical axes, a fixed eccentric guide rail and mechanism engaging said rail and operated by the movement of the car to turn said reflectors about both said lines, substantially as herein described.

6. In a heliomotor, the combination of a car adapted to turn about a fixed pivotal point, a series of reflectors carried thereby and mounted to turn about lines parallel to their horizontal and vertical axes, the fixed eccentric guide rail *g* formed and located so that its nearest point to the pivotal point lies in a north and south line through said pivotal point and intersecting said rail and its extremities gradually and evenly recede from said point, and mechanism engaging said rail and operated by the movement of the car to turn said reflectors about the lines parallel to their horizontal and vertical axes, substantially as herein described.

7. In a heliomotor, the combination of a car adapted to turn about a fixed pivotal point, a series of reflectors carried thereby and mounted to turn about lines parallel to their horizontal and vertical axes, the fixed eccentric guide rail *g* formed and located so that its nearest point to the pivotal point lies in a north and south line through said pivotal point and intersecting said rail, and its extremities gradually and evenly recede from said point, and mechanism engaging said rail and operated by the movement of the car to turn said reflectors about the lines parallel to their horizontal and vertical axes, consisting of a wheel engaging said rail, a sliding bar operated in and out by said wheel and connections from said bar to the reflectors, substantially as herein described.

8. In a heliomotor, the combination of a car adapted to move about a fixed pivotal point, connected reflectors carried by the car and pivoted so as to turn about lines parallel to their horizontal axes, tilting levers on the backs of said reflectors, adjustable links connecting said tilting levers, the fixed eccentric

guide rail, the wheel and slide bar operated thereby and the rock shaft with cranks connected with said sliding bar and with the connecting links of the tilting levers of the reflectors, substantially as herein described.

9. In a heliomotor, the combination of a car adapted to move about a fixed pivotal point, inclined supports carried thereby and axially pivoted at their ends, reflectors carried by the inclined supports, the fixed eccentric guide rail and connections engaging said rail and operating on the inclined supports to turn them and adjust their reflectors inwardly, substantially as herein described.

10. In a heliomotor, the combination of a car adapted to move about a fixed pivotal point, said car having axially turnable inclined supports, reflectors carried by said supports and pivoted thereto whereby they may turn about lines parallel to their horizontal axes, the fixed eccentric guide rail, the wheel engaging said rail and the sliding bar of the wheel, connections from said sliding bar to tilt the reflectors about the lines parallel to their horizontal axes and connections for turning their inclined supports to adjust said reflectors inwardly about lines parallel to their vertical axes, substantially as herein described.

11. In a heliomotor, the tiers of pivotally mounted reflectors having rearwardly extending tilting levers, links connecting said levers in each tier, and a weighted extension of the uppermost tilting lever to counterbalance the series, substantially as herein described.

12. In a heliomotor, the combination of the car adapted to turn about a fixed pivotal point and having the adjustable reflectors, the fusiform windlass and means for driving it and a connection between said windlass and the car whereby the latter is driven at the proper graduated speed, substantially as herein described.

13. In a heliomotor having the car with reflectors, means for operating said car and for effecting the movements and adjustments of its reflectors, said means including connected levers and links, and the adjustable connections between said levers and links consisting of the sliding clevis on the one part, having the spring clip sliding on the other part, and the set screws for holding them, substantially as described.

14. In a heliomotor, a car adapted to turn about a fixed pivotal point, a tier of central reflectors carried by the car and adapted to turn about lines parallel to their horizontal axes only and tiers of side reflectors adapted to turn about lines parallel to both their horizontal and vertical axes, substantially as herein described.

In witness whereof I have hereunto set my hand.

LUTHER W. ALLINGHAM.
